ORE CONCENTRATING APPARATUS

Tyra A. Philpott, Grand Junction, Colo.

Application July 27, 1951, Serial No. 238,872

4 Claims. (Cl. 209—168)

1

This invention relates to ore concentrating apparatus, and more particularly to apparatus for separately concentrating metallic ores of intermediate and heavy molecular weights.

It is among the objects of this invention to provide an improved ore concentrating device or apparatus which will concentrate ores of metals of intermediate molecular weights, such as those of gold, silver and copper, by a foam flotation process, and will concentrate ores of metals of heavy molecular weights, such as those of uranium or tungsten, by gravity and separately from the ores of metals of intermediate molecular weights; which is substantially continuous in operation and can be provided in different sizes to handle either small or large quantities of ore; which will receive pulverized ore directly from an ore mill and separately concentrate selected components, discharging the undesired portion of the ore as waste; and which is simple and durable in construction, economical to manufacture, and efficient and effective in operation.

Other objects and advantages will become apparent from a consideration of the following description and the appended claims in conjunction with the accompanying drawings, wherein:

Figure 1 is a side elevational view of ore concentrating apparatus illustrative of the invention, certain parts being broken away and shown in cross-section to better illustrate the construction thereof;

Figure 2 is an end elevational view of the ore concentrating apparatus illustrated in Figure 1, certain parts being broken away and shown in cross-section to better illustrate the construction of the apparatus;

Figure 3 is a fragmentary cross-sectional view on an enlarged scale on the line 3—3 of Figure 2; and

Figure 4 is a fragmentary cross-sectional view on an enlarged scale on the line 4—4 of Figure 1.

With continued reference to the drawings, the ore concentrating apparatus of the present invention comprises a supporting frame including a base structure 10 of rectangular shape, a top structure 11, also of rectangular shape and substantially parallel to the base structure, and vertically disposed posts, as indicated at 12, 13, 14, 15, 16 and 17, extending upwardly from the base structure 10 and supporting the top structure 11 on their upper ends above the base structure. The frame is reinforced by horizontally disposed cross members, as indicated at 18 in Figure 1 and 19, 20 and 21 in Figure 2.

A horizontally disposed drum 22 is mounted

2

above the top structure 11 of the frame by mounting brackets 23 and 24 disposed one at each end of the drum. The brackets 23 and 24 have bearing structures 25 and 26 at their upper ends which communicate with the interior of the drum through apertures in the end plates 27 and 28 of the drum, and a shaft 29 extends longitudinally through the drum and is journaled at its ends in the bearing structures 25 and 26.

10 Each of the bearing structures includes a packing assembly, as indicated at 30 and 31 in Figure 4, to prevent liquid from leaking out of the drum around the shaft. One end of the drum is disposed near one end of the supporting frame, and 15 a shaft-driving element, such as the belt pulley 32, is mounted on the corresponding end of the shaft 29.

Agitator paddles 33 project radially from the shaft at spaced apart locations therealong and at 20 angularly spaced apart locations therearound to thoroughly agitate a mixture in the drum to intermix the components of the mixture.

A boss or collar 34 projects upwardly from the side wall 35 of the drum at one end of the drum 25 and surrounds an inlet opening in the side wall of the drum.

A hopper 36 has at its lower end a boss or collar 37 secured to the top of the boss 34 on the drum to connect the interior of the hopper with the interior of the drum, and an ore chute 38 leads into the hopper at the upper end of the latter for delivering a mixture of pulverized ore and water into the hopper.

30 A manually controllable dispensing device 39 is supported above the top, open end of the hopper 36 by a bracket 40 mounted on the hopper, and is effective to dispense needed quantities of foam-producing chemicals into the mixture of pulverized ore and water in the hopper.

40 A bowl 41 having an open top, a closed bottom and an upwardly flaring side wall is mounted in the frame adjacent to and below the end of the drum 35 remote from the inlet boss 34 on the drum. An outlet fitting 42 is provided on the side wall of the drum at the bottom of the drum and at the end thereof remote from the inlet boss or fitting 34, and a conduit 43 communicates through the fitting 42 with the interior of the drum 35 and extends to the adjacent side of the bowl 41. The conduit 43 extends downwardly along the side of the bowl 41 and communicates with the interior of the bowl through an opening 44 provided in the side wall of the bowl near the bottom end of the latter.

45 With this arrangement, a mixture of pulverized

ore and water is fed into the hopper 36, foam-producing chemicals are added to this mixture from the dispensing device 39, and the water, ore and foam-producing chemicals are thoroughly intermixed in the drum 35 and delivered to the interior of the bowl 41 through the conduit 43.

A bearing support 45 extends diametrically across the open top end of the bowl and carries a bearing block 46 in which a bearing sleeve or bushing 47 is mounted with its axis substantially coincident with the axis or center line of the bowl 41. A second bearing sleeve 48 is disposed directly below the bearing sleeve 47 and mounted in a bearing block 49 supported by brackets 50 and 51, the ends of which remote from the bearing block 49 are secured to the bearing support 45 at diametrically opposite sides of the bowl 41.

A tubular drive shaft 52 is journaled in the bearing sleeves or bushings 47 and 48 and is substantially vertically disposed with its axis substantially coincident with the center line of the bowl.

Agitator blades or paddles 53 project radially from the shaft 52 at the lower end of the latter and at substantially equal angular intervals therearound, these paddles being disposed near the bottom wall 54 of the bowl. A wear pan 55 is disposed in the bowl between the blades 53 and the bottom wall 54. This wear pan has a central opening therein and inclines downwardly from its rim to the central opening, as is clearly illustrated in Figure 3.

A friction disc 56 is mounted on the tubular shaft 52 near the upper end of the latter and is supported on rollers 57 and 58 mounted on an auxiliary frame structure 59, and a bracket 60 extends upwardly from the auxiliary frame structure 59 near the edge of the friction disc 56.

The bracket 60 has a substantially vertically disposed slot or notch 61 therein, and a bearing block 62 is slidably mounted in this slot and receives a shaft 63. A friction wheel 64 is mounted on one end of the shaft 63 and frictionally engages the upper surface of the friction disc 56 near the periphery of the friction disc. A spring 65 is disposed between the bearing block 52 and an adjustable abutment 66 threaded into an aperture provided in the portion of the bracket 60 at the upper end of the slot 61 and resiliently presses the periphery of the friction wheel 64 against the upper surface of the friction disc 56 to provide a driving connection between the shaft 63 and the shaft 52.

A main drive shaft or line shaft 67 is substantially horizontally disposed between the frame base structure 10 and the top structure 11, and is journaled in bearings, as indicated at 68, 69, 70 and 71 supported on the frame posts 12, 13, 15 and 16, respectively. A main drive belt pulley 72 is mounted on the shaft 67 between the posts 12 and 13, and is preferably provided with a clutch 73 by means of which it can be manually connected to and disconnected from the shaft 67. The belt pulley 72 is driven by a suitable power plant, such as an electric motor or gasoline engine.

A belt pulley 74 is mounted on one end of the shaft 67 and connected by a belt 75 with the belt pulley 32 on the shaft 29, a belt tightener 76 being mounted on the frame post 12 and engaging the belt 75 to maintain this belt in driving association with the pulley 32. A second belt pulley 77 is mounted on the shaft 67 between the frame posts 14 and 15, and a belt pulley 78 is mounted on the end of the shaft 63 remote from

the friction wheel 64. A belt 79 connects the belt pulley 77 with the belt pulley 78, so that when the shaft 67 is driven, the shafts 29 and 63 are simultaneously rotated driving the mixing blades or paddles 33 and the agitating blades or vanes 53.

A cylindrical receptacle 80 is vertically disposed below the bowl 41 and connected at its upper end to the bottom wall 54 of the bowl. This receptacle communicates with the interior of the bowl through an opening in the bottom wall 54 of the bowl and through the opening in the wear pan 55, and a bottom end plate 81 is detachably secured to the receptacle 80 at the bottom end thereof by suitable means, such as the bolts 82 and 83.

A tube 84 is connected at one end to the receptacle 80 intermediate the length of the receptacle, and has its other end disposed adjacent the top of the bowl 41. This tube communicates through an opening 85 in the side wall of the receptacle with the interior of the latter and carries at its upper end a check valve 86 which permits air to enter the receptacle 80 through the tube 85, but precludes the exit of air from the receptacle through this tube.

A plunger rod 87 extends through the tubular drive shaft 52 and beyond the ends of the latter. A suction cup 88, formed of a suitable resilient material, such as vulcanized rubber, is secured on the lower end of the rod 87 and has a rim engaging the upper end of the receptacle 80 and having an internal diameter which is substantially the same as the diameter of the interior of the receptacle 80. The rim of this cup has an outside diameter substantially equal to the diameter of the central opening in the wear pan 55, so that the cup rim engages the top edge of the receptacle 80 surrounding the interior of the latter.

A horizontally disposed shaft 89 is journaled in bearing brackets 90 and 91 mounted on the top frame structure 11, and a crank 92 is mounted on one end of this shaft.

A walking beam 93 is pivoted intermediate its length on the upper end of a vertically disposed link 94, the lower end of which is pivotally mounted on a bracket 95 supported on the frame top structure 11, and has in one end a longitudinally extending slot 96 receiving the pin of the crank 92. At its other end the beam 93 is pivotally connected to the upper end of the plunger rod 87 by a pivot pin 97 to impart vertical reciprocatory movement to the plunger rod 87 upon rotation of the shaft 89 and crank 92. A belt pulley 98 is mounted on the shaft 89 at the end thereof remote from the crank 92, and a belt pulley 99 is mounted on the drive shaft 67 adjacent the belt pulley 77 and connected to the belt pulley 98 by a belt 100, so that the plunger rod 87 is reciprocated simultaneously with the rotation of the shafts 29 and 63 when the main drive shaft 67 is driven.

With this arrangement, while the mixture in the bowl 41 is agitated by the agitator paddles 53, the plunger rod 87 is moved up and down alternately compressing the plunger against the upper end of the receptacle 80 and raising the plunger a slight distance above the upper surface of the wear pan 55, as indicated in broken lines in Figure 3. When the plunger rod is raised, air is drawn into the receptacle 80 through the tube 84 during the first portion of the upward movement of the plunger rod, and, as the suction cup is raised above the wear pan, the

particles of heavy ore on the wear pan immediately around the central opening therein are permitted to fall past the plunger into the receptacle 80. When the plunger rod is then forced downwardly, the opening between the plunger rim and the upper end of the receptacle 80 is first closed, and then the air in the receptacle 80 is compressed and squeezed out of the receptacle around the rim of the plunger cup and into the bottom of the bowl 41, where it bubbles up through the mixture in the bowl, creating foam which floats non-wettable metallic particles, such as particles of gold, silver or copper, to the surface of the mixture in the bowl.

A skimmer mechanism is mounted near the top of the bowl and includes two horizontally disposed shafts 101 and 102 disposed in spaced apart and substantially parallel relationship to each other and respectively carrying belt rollers 103 and 104. The shaft 102 is disposed within the bowl near the upper open end of the latter and is supported by suitable brackets 105 depending from the bearing support 19. The other shaft 101 is disposed outside of the bowl and slightly above the shaft 102. A continuous belt 106 extends around the rollers 103 and 104 and carries outwardly projecting vanes or paddles 107 which extend transversely of the belt at spaced apart locations therealong.

A belt pulley 108 is mounted on one end of the shaft 101 and connected by a belt 109 to a belt pulley 110 mounted on the main drive shaft 67 for driving the skimmer belt 106 in a direction such that the vanes on the bottom portion of this belt move outwardly of the bowl 41.

A sheet metal hood 111 extends over the top and the inner end of the skimmer belt 106 and carries a swingable plate 112 at the outer end of the belt which engages the vanes 107 to clean material skimmed from the mixture in the bowl 41 from the vanes and to cause this material to fall from the outer end of the skimmer.

A bag-supporting hoop 113 is carried by the frame below the outer end of the skimmer, and a filter bag 114 is secured at its open, upper end to the hoop 113 by an adjustable clamp band 115 which surrounds the hoop and the bag near the upper end of the latter. This bag receives the material skimmed from the bowl 41 by the skimmer and retains the metal or ore particles therein, permitting the associated liquid to drain out into a discharge chute 115 disposed below the bottom end of the filter bag.

An outlet opening 117 is provided in the side wall of the bowl 41 near the bottom of the bowl and diametrically opposite the inlet opening 44. A discharge conduit 118 extends upwardly along the side of the bowl from the opening 117 to a location near the top of the bowl, and communicates with the interior of the bowl through the opening 117. A discharge chute 119 extends outwardly from the upper end of the discharge conduit 118, and adjustable gates 120 and 121 are provided in the discharge conduit, one in covering or partially covering relationship to the outlet opening 117, and the other in covering or partially covering relationship to the end of the chute 119 adjacent the discharge conduit 118.

By properly adjusting the gates 120 and 121, the rate at which the wettable portion of the ore, lighter than the portion which falls into the receptacle 80, is discharged from the bowl can be regulated.

The apparatus thus provides a continuous process receiving a mixture of pulverized ore and

water from an ore mill, adding foam-producing chemicals to the mixture of pulverized ore and water, thoroughly intermixing the mixture, floating the non-wettable ore or metal particles out of the mixture, concentrating the heaviest particles in a special receptacle and discharging the unwanted portion of the mixture.

The bottom plate 81 of the receptacle 80 can be periodically removed to discharge the heavy ore or metal particles from the receptacle 80, and this can be accomplished without discontinuing the operation of the device, if desired.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. Ore concentrating apparatus comprising a hopper for receiving pulverized ore and water, dispensing means adjacent said hopper for adding foam-producing chemicals to the mixture of pulverized ore and water passing through the hopper, a substantially horizontally disposed drum having one end in communication with the outlet of said hopper and receiving the mixture of pulverized ore, water and chemicals from the hopper, power-operated means extending through said drum for thoroughly intermixing the ingredients of said mixture therein, a bowl disposed adjacent the other end of said drum and receiving the mixture from the latter, a receptacle disposed below said bowl and communicating with the interior of said bowl through an opening in the bottom of said bowl, means including a check valve connected to said receptacle and effective to admit air into the receptacle while precluding exit of air therefrom except through the opening in the bottom of said bowl said receptacle having a manually controllable discharge opening at its bottom end, an agitator rotatably mounted in said bowl and including agitating vanes disposed adjacent the bottom of the bowl, a plunger including a cup of resilient material disposed in said bowl with the rim of said cup cooperating with the top end of said receptacle to pump air admitted to said receptacle from the latter into said bowl at the bottom of the bowl and control the passage of the heaviest particles of the ore from said bowl into said receptacle, said plunger and said receptacle being effective to cause the mixture in said bowl to foam, skimming mechanism disposed adjacent the top of said bowl for removing foam-floated particles of ore from the bowl, a filter receiving the ore and foam from said skimming mechanism and effective to separate the foam-floated particles of ore from the associated liquid, manually controlled discharge means in the side of said bowl for discharging liquid and wettable ore particles from the bowl, means connected to said plunger for imparting vertical reciprocating movement to the latter, and power means drivingly connected to said drum, said agitator and the plunger-reciprocating means for simultaneously rotating said drum and said agitator and reciprocating said plunger.
2. Ore concentrating apparatus comprising a supporting frame, a hopper mounted on said frame, a mixing drum mounted on said frame and connected at one end to the bottom of said hop-

per for the passage of material from said hopper into said mixing drum, a bowl mounted on said frame at the other end of said mixing drum and connected to the latter to receive material from said drum, a receptacle depending from the bottom of said bowl in communication with the interior of the latter, means connected to said receptacle admitting air into the latter while precluding the passage of air from the receptacle except through the opening in the bottom of said bowl, an agitator rotatably mounted in said bowl near the bottom of the latter, a wear pan disposed in said bowl between said agitator and said receptacle and having an opening therein at the upper end of said receptacle, a plunger vertically mounted in said bowl and including a suction cup of resilient material having a rim cooperating with the upper end of said receptacle for pumping air from said receptacle into said bowl and controlling the passage of heavy material from said bowl into said receptacle, mechanism mounted on said frame and connected to said plunger for imparting reciprocatory movement to the latter, means carried by said bowl providing a control discharge of material therefrom, a skimming device disposed at the top of said bowl for removing foam-floated material from the latter, a filter supported on said frame for receiving material from said skimming device, and power-actuated means mounted on said frame and drivingly connected to said mixing drum, said agitator, said mechanism and said skimming device.

3. Ore concentrating apparatus comprising a frame, a bowl mounted on said frame and having an open top end and a bottom wall having an opening therein, a receptacle disposed below said bowl and secured at its upper end to said bottom wall surrounding the opening in the latter, means mounted on said frame for supplying a conditioned mixture of pulverized ore, water and foam-producing chemicals to said bowl, a power-driven agitator in said bowl, air control means connected to said receptacle and admitting air to the latter while precluding passage of air therefrom except through the opening in the bottom of said bowl, a plunger vertically disposed in said bowl and including a suction cup of resilient

material having a rim cooperating with the upper end of said receptacle to pump air from said receptacle into said bowl and control the passage of heavy material from said bowl into said receptacle, power-actuated means mounted on said frame and connected to said plunger for imparting reciprocatory movement to the latter, and a skimming device extending into said bowl at the upper end of the latter for removing foam and foam-floated material from the bowl.

4. Ore concentrating apparatus comprising a bowl having an open top and a bottom wall provided with an opening, a receptacle disposed below said bowl and secured at its upper end to said bottom wall surrounding the opening in the latter, means adjacent said bowl supplying a conditioned mixture of pulverized ore, water and foam-producing chemicals to said bowl, a power-driven agitator in said bowl, air control means connected to said receptacle and admitting air to the latter while precluding passage of air therefrom except through the opening in the bottom of said bowl, a plunger vertically disposed in said bowl and including a suction cup of resilient material having a rim cooperating with the upper end of said receptacle to pump air from said receptacle into said bowl and control the passage of heavy material from said bowl into said receptacle, power-actuated means connected to said plunger for imparting reciprocatory movement to the latter, and a skimming device extending into said bowl at the upper end of the latter for removing foam and foam-floated material from the bowl.
